W. G. and Charles Reich, of Philadelphia, Pa.

Serial Patent No. 2,351. Dated July 10, 1925.

Design for a Base for a Hat

It is referred to in the drawing, which is given herewith, for further information.

It is also shown in perspective.

Q 1

Qs. 2351

West Downing Street, William and Philip Reed,
both of the City and County of Philadelphia, State of Pennsylvania,
have jointly invented and designed a new design for an umbrella
of which the following is a full, clear and exact description, reference
being had to the accompanying drawings, making part of this specification.

The umbrella is of an inverted cone
shape and is composed of various parts as
follows:—The handle is a straight piece of wood
about one and a half inches in diameter, having
a small hole through the middle, similarly in
the distal end, through which the handle of the cane
is passed, the cane being in all, a cane cane
about three feet long.

The canopy is a joint invention and designed
to secure by the joint invention and design for an umbrella
invent forth and for the
